UNITED STATES PATENT OFFICE.

WEBSTER B. WHEELER, OF WASHINGTON, DISTRICT OF COLUMBIA.

COIN OR CHECK CONTROLLED APPARATUS.

1,093,511.

Specification of Letters Patent. Patented Apr. 14, 1914.

Application filed August 6, 1909. Serial No. 511,574.

To all whom it may concern:

Be it known that I, WEBSTER B. WHEELER, a citizen of the United States, residing at Washington, District of Columbia, have invented new and useful Improvements in 5 Coin or Check Controlled Apparatus, of which the following is a specification.

This invention relates to a coin or check-controlled apparatus operative in conjunction 10 with different kinds of devices to permit a timed use of the latter, and it has been found particularly advantageous in connection with an electrically controlled optical appliance such as that disclosed by Patent 15 No. 709,837, granted to me September 23, 1902. The invention, however, is not limited to this particular application and essentially constitutes an improvement on the organization of devices disclosed by Patent 786,866 20 granted to me April 11, 1905.

The present invention has been devised to overcome disadvantages of operation of the mechanism disclosed by my Patent No. 786,866 and embodies features which are not 25 only beneficial to the user, but also to the person or persons having control or owning the apparatus.

The electrically controlled optical appliance disposed by my Patent No. 709,837 involves 30 automatically operating shutters which are opened by the closing of a circuit including the same to render the appliance or instrument clear for practical service or vision or to shut off vision through the appliance or instrument after a certain period of use.

The present apparatus embodies a circuit 35 which includes the magnetic device or solenoid disclosed by the said Patent No. 709,837, and which circuit is normally broken at two points, one of which is closed by a direct operation of the user of the apparatus and the other automatically closed by a coin or check of a predetermined character.

The present improved apparatus also embodies means for preventing fraudulent use 40 of the same and also for insuring the operator in the use of the optical appliance or device for a prescribed period of time in accordance with the adjustment of the apparatus.

A preferred embodiment of the present invention is disclosed in the accompanying drawings, and therein:—

Figure 1 is a transverse vertical section through the apparatus showing the latter in normal position and a coin or check as just having been inserted in the coin chute. Fig. 2 is a similar view in diagram illustrating the timing mechanism as having been set by a direct operation of the pull rod by the user and also showing the coin or check in a different position in the chute prior to its liberation and further travel in the chute to close one set of the normally open circuit elements, the remaining circuit elements normally open having been closed by the actuation of the timing mechanism. Fig. 3 is a sectional elevation of the coin chute, showing the coin or check as having reached its final position prior to liberation and operating by its weight to close the normally open circuit making elements adjacent thereto.

The apparatus represented has a casing 2 which may be of any desirable shape and material, and ordinarily consists of upper and lower chambers, the upper chamber receiving the coins or checks to bring about the action of the apparatus and rendered 25 accessible by a door which is usually locked and inaccessible except to authorized persons. The optical appliance, which is a pair of marine glasses 3, is adapted to be housed within the lower chamber of the 30 casing but may be exteriorly exposed on a drop door or shelf 4 at least until the apparatus has been set by the regular insertion of a coin or check to render the said glasses 35 usable. The drop door or shelf 4 is used for closing the lower compartment or chamber in which the glasses are disposed and said door may be locked to prevent access to the glasses within the lower chamber.

The working parts of the apparatus are 40 mainly contained within the upper chamber, and the controlling element of the timing mechanism is disposed in a portion of the lower chamber which is divided by an intermediate partition 5 so as to shut off the chamber for the glasses from any of the working parts or prevent exposure of the said working parts and access thereto from the exterior when the glass chamber is opened.

The apparatus is comparatively light and may be readily transported from one point to another, and the glasses 3 are secured by a suitable flexible cable or analogous means 6 on the partition 7 between the upper and lower chambers and forming a bottom for the upper chamber, the said cable being inserted through an opening 8 and having a portion thereof caught over a hook 9 secured on the partition or bottom 7, as clearly shown by Fig. 1. In the said upper chamber of the casing is an inclined coin or check chute or run-way 10, the entering end of which coincides with a slot 11 in a face plate 12 on the front upper portion of that side of the casing 2 which stands toward the user, the extremity of the chute or runway 10 secured to the side of the casing having a vertical extension 13 which serves as a preliminary receiver for the coin or check. Between the receiver and the main body of the chute or run-way below, a passage 14 is provided, said passage being normally contracted to prevent movement therethrough of any coin until a certain operation ensues, by a slide or controller 15 movable on the upper edge of the chute or run-way 10 and having its forward extremity 16 normally projected partially across the passage 14, as shown by dotted and full lines in Figs. 1 and 3. The slide or controller 15 is mounted in suitable guides 16^a fixed on the chute or run-way 10 and projecting laterally from one side edge of the said slide or controller is a pin 17. The rear end of the slide or controller has an upwardly projecting forwardly inclined slotted head 18 continually engaged by a pin or stud 19 projecting laterally from the upper goose neck or curved extremity 20 of a coin or check liberating lever 21 fulcrumed on the side of the chute or run-way as at 22. The terminal of the goose-neck or curved extremity 20 is disposed close to one side of the chute or run-way 10 and has a stop pin or stud 23 projecting through and movable in an arcuate slot 24 in the said side of the chute or run-way, the said pin or stud 23 extending far enough across the interior of the chute or runway to stop the movement of a coin or check in the chute slightly in advance of a rear bottom outlet 25^a when the pin or stud 23 is down in normal position. The coin or check liberating lever 21 has a rocking movement imparted thereto and the pin or stud 23 rides freely upwardly and downwardly in the arcuate slot 24. Fulcrumed on the side of the chute or run-way 10 opposite that over which the goose-neck or curved extremity 20 of the lever 21 has movement an intermediate coin or check stop is applied and consists of an intermediately fulcrumed lever 25 having an upper slotted head 26 in which the pin or stud 17 has free movement 65 and a lower stop pin or projection 27 ex-

tending into the chute or run-way 10 through an elongated arcuate or segmental slot 28, the stop 25 being given sufficient throw or movement to clear the chute or runway and having such timed actuation as to clear the chute or run-way while the pin or stud 23 carried by the goose-neck or curved extremity 20 of the lever 21 is down in normal position. The intermediate coin or check stop is normally elevated, as shown by Fig. 1, and when the slide or controller 15 is actuated to clear the passage 14 and permit the coin or check to pass into the main body of the chute or run-way 10 said intermediate stop is lowered and brought into the position shown by Fig. 2 and holds the coin or check in the forward extremity of the chute or run-way, the goose-neck or curved extremity of the lever 21 being at this time elevated, and when the intermediate stop is returned to normal position by the release of the slide or controller 15 and the forward movement of the latter, the movement of the said intermediate stop is timed to maintain control of the coin or check until the pin or stop 23 is down in its normal position and disposed to prevent liberation of the coin or check through the outlet 25^a. The mechanism coöperating with the chute or runway 10 as just explained is actuated through the medium of a setting bar or rod 29 extending through the front side of the casing and provided with a pull-head or knob 30. This setting bar or rod 29 is mounted in a sheath or tube 31 suitably slotted to expose a portion thereof, as indicated by dotted lines in Fig. 1. Projecting outwardly from the rod or bar 29 is a pin or stud 32 extending through a slot 33 in the lower extremity of the coin or check liberating lever 29, and attached to the lower end of the latter lever and to the rear end of the casing is a spring 34 which tends to restore all of the parts to normal position. When the rod or bar 29 is drawn outwardly the lower extremity of the lever 21 is moved in the same direction and the spring 34 distended, and as soon as the said bar or rod is released, the spring 34 exercises its retractile influence and instantly draws the bar or rod rearwardly and restores the lever 21 to normal position. When the lever 21 is moved outwardly with the bar or rod 29 as just explained, the upper gooseneck or curved extremity 20 of the said lever is thrown rearwardly and draws in the same direction on the slide or controller 15 through the medium of the slotted head 18 and the pin or projection 19, and at the same time the intermediate stop 25 is moved from the position shown by Fig. 1 to that illustrated by Fig. 2 and the coin or check inserted and preliminarily held in the extension 13 is permitted to fall into the forward extremity of 130

the chute or run-way 10 in advance of the pin or projection 27 and the latter holds the said coin or check in the advance part of the chute until the bar or rod 29 is released, and 5 as before explained, the movement of the intermediate stop and of the goose-neck or curved extremity 20 of the lever 21 is so timed that the intermediate stop will not release the coin or check until the pin or stud 23 is fully lowered and ready to serve as a 10 final stop for the coin or check. By this means the operator or user is protected as to the service of the coin or check which he has inserted and the electrical part of the apparatus is rendered active in clearing the marine glasses for sighting purposes.

In the bottom of the chute or run-way 10 a weight-controlled or gravitating connector is mounted and consists of an intermediately 20 fulcrumed lever 35, the fulcrum being located nearer the front extremity of the lever and thus dividing the latter into a rear long arm and a forward short arm, the latter being shouldered as at 36 to engage a corresponding shoulder 37 formed in the bottom 25 of the chute or run-way 10 to prevent depression of the forward arm of said lever. Depending from the forward arm of the lever is a contact hook 38 having its free end disposed below and in position to engage a 30 horizontal metallic contact plate or member 39 carried by a rod 40 adjustable vertically in a binding post 41 to compensate for modifications in the movement of the weight-controlled or gravitating connector in accordance 35 with the coins or checks introduced into the chute or run-way to actuate the apparatus. A coin or check liberated by the intermediate stop moves through the chute or 40 run-way over the lever 35 and when it reaches the rear extremity of the latter, or as it is approaching said extremity, the said lever is tilted downwardly and when the coin or check strikes the pin or stud 23 the 45 rear extremity of the lever is fully depressed and the free end of the hook 38 is held in contact with the plate or member 39, the parts being so proportioned that the coin or check will be prevented from moving farther 50 toward the outlet 25 until the pin or stud 23 is raised by a subsequent actuation of the lever 21 when another coin or check is inserted in the slot 11 and the rod or bar 29 pulled outwardly to permit the said second 55 coin or check to pass into and through the main portion of the chute or run-way, as hereinbefore explained, and when the said lever is so operated the coin or check which was first inserted and has been held in the 60 chute to maintain contact between the hook 38 and plate or member 39 will be liberated from the chute and fall to the partition or bottom 7.

The hook 38 together with the lever 35 65 and plate or member 39 constitutes a main

circuit closer, and though the means for operating this circuit closer is illustrated in the form of a coin chute to show one practical application of the invention it is only necessary to render the more essential features of the invention operative and effective in performing their desired function that the contact between the hook 38 and the plate or member 39 be established and the tilting action of the lever 35 may be accomplished in any other manner. In other words the remaining features of the invention are not dependent upon the specific form of coin chute for their operation so long as the contacting elements consisting of 70 the plate or member 39 and the hook 38 are retained to constitute the main circuit closer and wherein the hook is movable with relation to the plate or member. The frame or support for the lever 35 and the latter 75 will be connected to a source of electrical generation and the support for the plate or member 39 will also be connected to the same source of electrical generation so that the hook and the plate or member serve as 80 the terminals for the electric circuit controlling the more essential features of the invention.

The timing mechanism in the improved apparatus is very simple and differs radically from that disclosed by my Patent No. 786,366, and possesses many features of advantage, among which may be noted positive action due to the use of air as the controlling medium. This mechanism essentially comprises a bellows reservoir 42 having a suitable flexible body with upper and lower heads 43 and 44 fixed to said body, the upper head being provided with an interiorly located weight 45 at the center, a pin-hole 46 at one side of the center, and a tubular stem 47 rising from the upper side of the center and freely movable through an opening 48 in the partition or bottom 7. The upper end of the tube 47 has a reduced opening 49 produced by an inwardly extending annular flange 50, and fixed to the upper end of the tube or tubular stem 47 is a contact disk or plate 51 of metal. Freely movable in the tubular stem 47 is a weight 52 having a cord 100 or chain 53 secured to the upper end thereof and trained over a grooved pulley or sheave 54 held by an arm 55 attached to the rear of the casing. The opposite end of the cord 53 is attached to a pin or stud 56 on the rod 105 or bar 29 and is movable with the latter so that when the said rod or bar is drawn outwardly the weight 52 is moved upwardly 110 through the tubular stem 47 until it strikes the flange 50 when the said stem and head 115 53, together with the body of the bellows reservoir, are drawn upwardly and create a suction in relation to the head 44. The head 44 has a central inlet opening 57 in communication with a duct 58 opening through 120 125 130

the rear side of the apparatus, the said head 44 being hollow as at 59 and having communication through an opening 60 in a bottom plate 61 with the duct 58. Over the 5 opening 57 a yieldable or elastic valve strip 62 is secured, sufficient play being given this strip to permit air to enter the reservoir when suction is exerted on the strip by the upward movement of the head 43. To insure the return to normal closing position 10 of the strip 62 a weight 63 is fixed on the center thereof over the inlet opening 57 so that no air will be permitted to escape at this point but is all forced to pass out 15 through the pin-hole or reduced escape aperture or opening 46. After the head 43 has been operated to fill the reservoir with air through the medium of the setting rod or bar 29 and the said rod or bar is retracted 20 within the apparatus, the weight 52 descends in the tubular stem 47 and there is no resistance to the gradual collapse of the air reservoir. This collapse ensues very gradually as the air escapes slowly through the 25 pin-hole or opening 46, and as the quantity of air gradually lessens in the air reservoir the head 43 settles or gravitates toward the head 44, drawing the tubular stem and disk 51 downwardly therewith, and as will be 30 more fully hereinafter explained the said disk 51 by its depression or at the termination of a predetermined interval of time will break an electric circuit and render the marine glasses inoperative for sighting purposes by closing the shutter means thereof. Two metal contact arms 64 and 65 are disposed to operate with the disk or plate 51, both arms having inner bent terminals 66 and each fulcrumed on a post, the arm 64 35 being pivotally supported by a post 67 and having a spring 68 attached thereto which tends to draw the said arm 64 downwardly and maintain the bent end 66 thereof in contact with the disk 51, the said arm 64 40 being unlimited in its downward movement and thereby always held in contact with the said disk. The arm 65 is fulcrumed on a post 69 having a laterally projecting head 70 in which is mounted a set-screw 71 freely 45 adjustable to engage the adjacent end of the arm 65 to limit the downward movement thereof or the bent end 66 in contact with the disk 51 to break contact with said disk 55 after a certain interval of time during the descent of the disk and tubular stem 47 and thereby break the electric circuit in which the post 69 and arm 65 are included.

The electric current is derived preferably 50 from a dry cell 72, though other means may be used, and said cell is disposed in a metallic socket 73 depending from the intermediate partition of bottom 7 of the upper chamber. Within the lower extremity of 55 the socket 73 a spring 74 is mounted and

makes an electric contact with one pole of the cell when the latter is pressed downwardly thereagainst and by this means an electric connection is set up between the cell and socket. Adjacent to the upper extremity of the socket 73 a guide rod or post 75 rises from the partition or bottom 7 and thereon a pressure arm 76 is slidably mounted and adapted to be held in fixed adjustment by a set-screw 77 engaging a portion 70 of the arm and impinging against the rod or post 75. The free end of the pressure arm 76 is provided with a contact plate 78 which is caused to engage with the remaining pole of the cell at the top of the latter, the said arm 76 also having the function of holding the cell down in place in the socket and obviating movement of the said cell during transportation of the apparatus, for instance. The cell 72 may be readily removed 80 and revivified when occasion requires or replaced by another similar device simply by loosening the arm 76 and elevating said arm on the rod or post 75 and without requiring detachment or attachment of electrical connections, such as wires. 85

As disclosed in my Patent No. 709,837, the cable or cord 6 incloses two wires or electrical connections to establish a circuit with the magnetic device or solenoid controlling the shutters, and these wires are attached to metallic terminals 79 and 80 having suitable binding screws, as illustrated by Fig. 2. A wire 81 is attached to the terminal 79 and to the binding post 41 adjustably supporting the contact plate or member 39 through the medium of the rod or post 40. To the terminal 80 a wire 82 is attached and also to the base of the rod or post 75, and from the socket 73 a wire 83 runs to the base of the post 69 supporting the arm 65. From the base of the post 67 on which the arm 64 is mounted a wire 84 runs to the upper portion of the extension 13 of the chute or run-way 10, as clearly 90 shown by Fig. 2, and as all the parts thus connected are of metal a reliable metallic circuit will be established when the hook 38 is in contact with the disk or member 39 and both arms 64 and 65 are in contact with 95 the disk or member 51. 100

The operation of the apparatus will be readily understood from the foregoing description, but to enumerate the several actuations from the insertion of the coin or 105 check to the final automatic closure of the shutter means in the marine glasses, the procedure and operation of the several elements are as follows: The person desiring to use the glasses inserts a coin or check in the coin slot 11 and the said coin or check is retained in the extension 13 by the forward end of the slide or controller 15 normally contracting the passage 14, as shown by Fig. 1. The user or operator then pulls the rod or bar 110 120 125 130

29 fully outwardly against the resistance of the spring 34 and by the operation of the intermediate stop 25, slide 15 and lever 21 as hereinbefore explained the coin or check is permitted to descend into the outer extremity of the chute or run-way 10, as shown by Fig. 2, and at the same time the cord 53 has had sufficient stress exerted thereon to cause the weight 52 to pull the tubular stem 47 and head 43 of the bellows reservoir 42 upwardly and charge the said reservoir with a quantity of air. When the tubular stem is thus pulled upwardly the bent ends 66 of the arms 64 and 65 are brought into contact 10 with the disk 51, the said arms 64 and 65 being elevated against the resistance of the springs 68 and 65^a, the latter spring being attached to the arm 65 in a manner similar to the attachment of the spring 68 to the arm 64. The coin or check remains in the outer or forward extremity of the chute or run-way 10 so long as the rod or bar 29 is held drawn outwardly as shown by Fig. 2. When the bar or rod 29 is released the spring 25 34 attached to the lower end of the lever 21 quickly restores said rod or bar to normal position, and the upper goose-neck or curved extremity 20 of the lever 21 is caused to move downwardly, the slide or controller 30 15 simultaneously shifted forwardly to again constrict the passage or throat 14, and the intermediate stop embodying the lever 25 thrown around to release the coin or check and the latter then travels over the weight-controlled or gravitating connector or lever 35 and causes the hook 38 to engage the contact plate or member 39 and completes the circuit, which will be from the metallic terminal 80 through wire 82 to the base of the 40 post 75, through the cell 72, spring 74, metallic socket 73, by wire 83 to the base of the post 69 and arm 65 to disk 51, arm 64 and post 67 by wire 84 to the upper portion of the extension 13 of the chute or run-way 45 10 and through the latter by the hook 38 to plate 39 and rod 40 to binding post 41 and by wire 81 to the remaining terminal 79. The moment this circuit is completed the magnetic device or solenoid in the marine 50 50 glasses will be energized to operate the shutter means to clear said glasses for sighting purposes and the user is at liberty to view objects and scenes through the glasses.

During the use of the glasses the check or 55 coin will be held in the chute or run-way 10, as shown by Fig. 3, and the contact between the hook 38 and the plate 39 will be constantly and positively maintained through the medium of the coin or check 60 holding the weight-controlled connector or lever 35 in depressed position. The head 43, tubular stem 47 and disk 51 will immediately start to gradually lower by the escape of the air through the pin-hole or opening 65 46, and as the disk 51 gradually falls the bent ends 66 of both arms 64 and 65 will follow in contact therewith for a certain length of time or until the fulcrumed extremity of the arm 65 engages the end of the screw 71, when the contact between the end 70 66 of the arm 65 and the disk 51 will be broken by a continued descent of the said disk and the circuit likewise simultaneously broken. As soon as the circuit is broken by the operation just explained the magnetic 75 device or solenoid in the marine glasses is deenergized and the shutter means will be instantly operated to close the said glasses and thus prevent further use of the latter until another coin or check is inserted in the 80 slot 11 and the same operation pursued. The coin or check which is utilized to operate the mechanism and occupying the position illustrated by Fig. 3 remains in the chute or run-way 10 until a subsequent coin 85 15 is inserted in the slot 11 and extension 13 of the said chute and the first used coin or check is liberated only when the rod or bar 29 is drawn outwardly to give entrance to a subsequent coin or check into 90 the chute or run-way 10, and as soon as the coin or check first introduced is liberated from the chute or run-way the weight is relieved from the connector or lever 35 prior to engagement with the said connector or lever of the second coin or check and the contact between the hook 38 and the plate or member 39 is immediately broken and will not be restored until the second coin or 95 20 check is liberated by the intermediate stop or lever 25 and travels over the connector or lever 35 and reaches the position shown by Fig. 3. This particular operation has been devised to prevent fraudulent or repeated use of the apparatus by the introduction 100 25 or through the medium of a single coin or check and also to insure the user in the operation of the glasses. If an attempt is made to use the apparatus without properly inserting a coin or check and while a previously introduced coin or check remains in the chute or run-way 10 and occupies the position shown by Fig. 3, such use is defeated 105 30 the moment the bar or rod 29 is drawn outwardly, as the first introduced coin or check 110 35 will be liberated and fall through the outlet 25 into the upper chamber of the apparatus and at the same time break the contact between the hook 38 and the plate or member 39 and as a consequence the shutter means in the marine glasses will remain closed. The user or operator regularly inserting a coin or check is protected or insured as to the operation of the shutter 115 40 means in the marine glasses to clear the latter by the intermediate stop or lever 25. But for this intermediate stop a coin or check would pass fully through and out from the chute or run-way 10 the instant the 120 45 rod or bar 29 was drawn outwardly and the 125 50 55 60 65 70 75 80 85 90 95 100 105 110 115 120 125 130

circuit would not be completed and hence the shutter means in the marine glasses would remain closed. By following instructions or explanations as to the use of the apparatus and which will be disposed in a conspicuous position on the front of the casting, an operator will readily ascertain that by applying the glasses to the eyes after inserting a coin or check the said glasses will be cleared for vision by a single outward pull and release of the rod or bar 29, and by following the simple instructions loss of the coin or check without use of the glasses will be prevented.

15. By way of example and explanation, marine glasses have been hereinbefore particularly referred to as rendered usable by the actuation of the apparatus, but it will be understood that any other devices might be substituted for the marine glasses with similar operative and inoperative results.

18. The electric current generator or cell 72 and the electric circuit are shown included in the equipment of the apparatus to render the complement of the latter complete for portable purposes. The apparatus may, however, be used in theaters, lecture halls and the like and control the use of optical glasses, and under these conditions the supply of electric current may be located at a distance from the several apparatuses and under the control of a suitable switch-board. This particular application would not involve a modification of the apparatus as the circuit would be the same in each glass controlling apparatus and the timing mechanism would similarly come into play as well as the coin chute and other devices controlling the circuit so as to make and break the latter, as hereinbefore fully explained.

What is claimed is:

1. In an apparatus of the class specified, a pull means, a timing mechanism connected to and rendered active by the pull means and carrying an electrical contact device, movable contact elements engaging the contact device of the timing mechanism, one of said movable contact elements being released from contact with the timing mechanism after a certain lapse of time, a main circuit closer embodying two coöperating elements, one of said elements being movable toward and from the other, and an electric circuit including the main circuit closer and the movable contact elements engaging the contact device of the timing mechanism.

2. In an apparatus of the class specified, an electric circuit, a timing mechanism having circuit making and breaking means co-operating therewith, a pull device connected to the timing mechanism and operating to make the circuit therewith, and a main circuit closer having movable means to open and close the said electric circuit and elec-

trically connected to a part of the timing mechanism.

3. In an apparatus of the class specified, an electric circuit, a timing mechanism having a contact device, movable contact elements for engaging the contact device of the timing mechanism to make the circuit through said timing mechanism, one of the said elements being automatically disengaged from the contact device of the timing mechanism at a certain interval to break the circuit through the timing mechanism, a main circuit closer preliminarily operated to render all the parts and elements of the electric circuit active when the circuit is made through the operation of the timing mechanism, and means associated with the said timing mechanism for actuation by the user to set the timing mechanism and complete the circuit through said mechanism.

4. In an apparatus of the class specified, an electric circuit, timing mechanism having a vertically movable element with a contact at its upper extremity, movable contact elements to engage the contact at the upper extremity of the movable elements of the timing mechanism, a main circuit closer, one of said contact elements being automatically disengaged from circuit making contact with relation to the contact of the movable element of the timing mechanism, the circuit being first broken through the timing mechanism and then through the circuit closer, and pull means connected to the movable element of the timing mechanism and operable by the user to actuate said mechanism and complete the circuit through the latter.

5. In an apparatus of the class specified, a main circuit closer provided with fixed and a movable projecting means arranged for contact, a timing mechanism comprising a bellows having a movable element with a contact device, a pull means arranged for operation by the user of the apparatus and connected to the movable element of the bellows, movable contact devices arranged to engage the contact with the movable element of the bellows, one of said contact devices being automatically disengaged from circuit making contact with the said contact of the movable element at a certain interval of time, and an electric circuit including all the foregoing devices and mechanisms.

6. In an apparatus of the class specified, a timing mechanism consisting of a bellows reservoir having a valved bottom and a gravitating top with an escape opening therein and a tubular stem rising therefrom and carrying a contact disk, exteriorly engageable pull means for the user, a cord attached to said exteriorly engageable means and provided with a weight mounted and freely movable in said tubular

stem, the operation of the exteriorly engageable pull means filling the bellows through the movement of the gravitating top and tubular stem by means of the weight and cord; movable circuit making arms to engage the said disk, the one arm being limited in its movement to automatically disengage it from circuit making contact with relation to the disk, a main circuit closer, and an electric circuit including the said timing

mechanism and circuit making arm and closed and opened by said main circuit closer.

In testimony whereof I have hereunto set my hand in presence of two subscribing ¹⁵ witnesses.

WEBSTER B. WHEELER.
